UNITED STATES PATENT OFFICE

2,531,119

AUTOMATIC DOOR

Ronald Everitt, Aurora, Ill.

Application September 25, 1946, Serial No. 699,232

3 Claims. (Cl. 268—37)

1

My invention, which pertains to doors of the type employed on garages and similar structures has as an important objective the provision of a simple and inexpensive door structure which may be swung about a horizontal axis to expose a relatively large opening such as the vehicle opening in a garage, hangar, or the like, and which may be automatically actuated by a novel vehicle-operated mechanism.

Overhead doors save space and are easier to operate than conventional doors hung to swing about a vertical axis. They are particularly advantageous where the opening is large since the weight of the door may be counterbalanced and the effect of wind pressure substantially reduced. But as heretofore made, they have been quite costly since it has been necessary to form a number of transverse joints in such doors which impart sufficient flexibility to the door structure to permit movement along a curved track or guide.

Doors for large openings such as hangar doors are often necessarily automatically actuated, employing diverse forms of mechanical and electrical apparatus to accomplish the operation but substantially all such mechanisms heretofore known have been relatively costly and require continuous maintenance to insure operation. The simplicity, strength and light weight of my door permits the employment of a simple and durable mechanical door-actuating means which will operate reliably without excessive maintenance throughout extended periods of time.

Briefly my door comprises a rigid arcuate section of suitable material such as sheet metal or wood reinforced as necessary and provided with arms extending radially inwardly to a horizontal shaft or other support adapted to permit partial rotation of the door. The arms extending from the door may be disposed either within or without the building depending on whether or not it is desired to swing the door upwardly over the roof, as would be the case where external arms are employed, or upwardly beneath the roof as when the arms are within the building. Suitable seals are formed on the door, the walls, and the roof of the building to prevent the entry of rain and wind. A counterweight is customarily employed to hold the door in a closed position and to close the door automatically after opening, suitable catches being provided to retain the door in either position.

Since only simple arcuate movement is required to actuate the door, my automatic opening device comprises a system of levers or other means

linking the arms extending inwardly from the door to a trackway extending outwardly beyond the door and hinged for movement about a horizontal axis. The trackway is arranged in such manner that as the wheels of a vehicle engage the trackway, a movement of the trackway about the horizontal axis is produced which is in turn communicated through the system of levers causing the door to operate. As the vehicle passes through the door and the rear wheels leave the trackway, the door is closed by the counterweight. Both the door herein described and the door-actuating mechanism are particularly well adapted for use on garages of the type described in my Patent No. 2,282,324 dated May 12, 1942, the description of which, in so far as consistent, is incorporated and made a part hereof by reference.

Referring to the drawings,

Figure 1 is a partially sectioned diagrammatic elevation of my automatic doors;

Figure 2 is a top view of the device illustrated in Figure 1;

Figure 3 is a section taken along the lines 3—3 of Figure 1; and

Figure 4 is a modification of the device illustrated in Figure 1.

As shown in Figure 1, a garage, generally designated 10, having side walls 11 and a roof 12 is provided with a trackway 13 extending outwardly beyond the ends of the walls 11, the opposite end of the garage being closed by an end wall 14. The trackway 13 includes a horizontal web or base 16 of sufficient width to receive the wheels of a vehicle and may be provided with one or more vertical flanges 17 to guide the wheels and prevent their leaving the trackway. The outer ends of the trackway 13 may be flared as at 18 to assist the driver of the vehicle in placing the wheels on the trackway. If desired, rollers 19 may be journaled to the outer ends of the trackway 13 to permit a sliding movement thereof along the surface of the ground, or along a suitable plate of hard material. The trackway 13 is provided with a transverse hinge 21 disposed between the ends of the trackway which may suitably comprise a pin 22 extending through ears 23 formed integrally with the web 16. The inner end of the trackway 13 is secured to a shaft 24 which is journaled in the side walls 11 of the garage. Upwardly extending arms 26 are secured at one end to the outer ends of the shaft 24, which extend outwardly beyond the walls 11.

The side walls 11 and the roof 12 define a vehicle opening closed by a door, generally desig-

nated 27, which comprises a rigid sheet or plurality of sheets of suitable material such as wood or metal having a configuration similar to a surface section of a right cylinder. The ends of the side walls 11 are provided with an outwardly extending flange 28 and are curved to receive a channel 29 formed, for example, by a reverse turn of the edges of the door 27. Arms 31 are secured as by welding to the outer edges of the door 27 and extend radially inwardly to a center corresponding to the axis of the cylinder of which the door 27 forms a surface segment. Center hubs 32, preferably integral with the arms 31, are journaled to horizontal stub shafts 33 which may be suitably secured to the walls 11 or to other suitable support means. The upper end of the door 27 is provided with a downwardly extending flange 34 which, when the door is in closed position, engages a channel 36 formed in the end section of the roof thus forming a weatherproof joint which in combination with the channel 29 and flange 28 effectively seals the opening against the entrance of wind and rain. Gaskets may, of course, be employed in these joints, if desired.

Arms 37 extend outwardly from the hubs 32 and support adjustable counterweights 38 of sufficient mass to substantially overcome the weight of the door 27 and assist in raising and lowering the door. The lower edge of the door 27 is suitably notched as at 39 to receive the trackways 13 and permit the lower edge of the door 27 to engage the sill of the garage. A flexible plate 41 of a material such as rubber may be secured to the underside of the trackway 13 and to the floor of the garage 10 to seal the space between the floor and the bottom of the trackway when the door 27 is closed. Alternatively, the plate 41 may comprise a section of metal hinged to the underside of the trackway 13 and disposed to an angle to the floor of the garage 10 in such manner that when trackway 13 is lowered, the edge of the plate 41 will slide along the floor, and as the trackway rises, will return by gravity to a position in which it closes the opening between the trackway and the floor.

A link 42 is pivotally secured to the free end of arms 26 and to arms 37 between the hub 32 and the counterweight 38, the length of the link 42 being such that with the door 27 in closed position, the hinged center portion of the trackway 13 is maintained a distance above the horizontal. As the front wheels of the vehicle entering a garage engage the trackway 13, the weight of the vehicle forces the trackway downwardly moving the outer end 19 thereof outwardly and causing a partial rotation of the shaft 24. This in turn moves the arms 26 in a clockwise direction, drawing the link 42 to the right and forcing the door 27 upwardly about the shaft 32 into open position, as indicated by dotted lines in Figure 1. As long as the wheels of the vehicle engage the trackway 13, the door 27 will remain open and, if the wheel base of the vehicle is less than the overall length of the trackway 13, it is obvious that the door 27 will remain open until the rear wheels of the vehicle leave the trackway, at which time the door 27 will be free to close by the action of counterweights 38. If the wheel base of the vehicle is excessively long, it is of course obvious that suitable catches may be employed to maintain the door in an open position. As the vehicle leaves the garage, the reverse of the above described sequence of operation occurs, the rear wheels of the vehicle engaging the inner end of

the trackway 13 and thus forcing the door 27 into open position.

It is of course obvious that several other types of linkage may be employed to interconnect the trackway and door. A modified form of linkage is illustrated in Figure 4 wherein the operating mechanism is disposed within the walls of the garage, a shaft 32 being secured to the inner surface of the walls 11 and the arms 31 being suitably secured to the inner surface of the door 27. In this modification arms 43, preferably somewhat longer than the previously described arms 26, are secured to the shaft 24. A cable 44 extends from the end of arms 43 over a winch 46, having a handle 47, to arms 31. The winch 46 may be of conventional design secured to a wall 11 of the garage. If desired, a winch shaft 48 may extend through the wall 11 of the building and the handle 47 be secured to either end thereof to permit operation of the winch from the inside or outside of the garage. As the wheels of a vehicle engaging the trackway 13 force the trackway downwardly, the arms 43 are moved by shaft 24 in a clockwise direction, drawing the cable 44 around the winch 46, thus pulling the arms 31 and the door 27 upwardly to open position beneath the roof 12 of the garage. Since the door 27 in open position is wholly within the garage, the roof 12 is provided with a downwardly extending flange 49 which engages the upper edge of the door 27 in its closed position forming the weatherproof joint. If it is desired to open or close the door 27 manually, the winch 48 actuated by the handle 47 may be employed.

From the foregoing it may be seen that my door can be simply and inexpensively formed and provides a highly durable, strong closure without the necessity of weakening the structure by providing one or more horizontal joints therein. All of the advantages of mechanical types of overhead doors are preserved without the necessity of incorporating expensive, complicated and troublesome mechanism for guiding a door along an irregular path. Because of its curved cross section, my door has the ability to resist extraordinary wind pressures, and because of its inherent strength can be formed of lighter materials. The simplicity of my door-actuating mechanism obviously eliminates many of the troublesome complications in mechanisms necessarily employed by the more complex devices of the prior art and will therefore operate for extended periods of time without maintenance or repair.

I am aware that in view of the foregoing disclosure those skilled in the art will be enabled to modify the herein described structures as required by local conditions and I do not therefore wish to limit myself specifically to the arrangement of parts herein described except in so far as defined by the appended claims.

I claim:

1. A door and means for opening the door on the approach of a vehicle, said door being mounted on aligned horizontal pivots, one at each side of the door, for arcuate rotary movement about said pivots to open and closed positions, said means for opening the door comprising an arm rotatably mounted on one of said pivots and connected to the door to operate the door when the arm is moved, a track device outside the door and leading to the doorway and comprising two members hinged together on a horizontal axis at their meeting ends, the other end of one of said track members being fixed to a rockable

horizontal shaft and the other end of the other of said track members being unrestrained, a second arm rigid with said shaft and connected by link means with the said door operating arm, whereby when the door is in closed position the hinged ends of said track members are held in raised position and whereby when a vehicle traverses said track members the hinged ends thereof will be forced downward and operate said horizontal shaft, arm members and link means to open the door.

2. A door and means for opening the door on the approach of a vehicle, said door being mounted on aligned horizontal pivots, one at each side of the door, for rotary movement about said pivots to open and closed positions, said means for opening the door comprising an arm rotatably mounted on one of said pivots and connected to the door, a rockably supported horizontal shaft connected by link and lever means to said arm to move the door when the shaft is rocked, and upwardly inclined downwardly movable means rigidly connected with said shaft to rock the same, said movable means having a portion extending outside the door in position to be traversed and downwardly moved by an approaching vehicle.

3. A door and means for opening the door on the approach of a vehicle, said door being mounted for rotary movement about a horizontal axis to open and closed positions, said 30

means for opening the door comprising a horizontal rockably supported shaft, link and lever means connecting the shaft to the door to move the door when the shaft is rocked, and upwardly inclined downwardly movable track means including a member rigidly connected with said shaft to rock the same, said movable track means having a portion located on the approach side of the doorway and in position to be traversed and downwardly moved by an approaching vehicle.
